UNITED STATES PATENT OFFICE.

ALFRED B. DAVIS, OF PHILADELPHIA, PENNSYLVANIA, ASSIGNOR, BY MESNE ASSIGNMENTS, OF ONE-HALF TO ERNEST H. CHASE, OF PHILADELPHIA, PENNSYLVANIA.

FOUNTAIN-PEN.

SPECIFICATION forming part of Letters Patent No. 766,759, dated August 2, 1904.

Application filed December 1, 1903. Serial No. 183,373. (No model.)

To all whom it may concern:

Be it known that I, ALFRED B. DAVIS, a citizen of the United States, residing in Philadelphia, Pennsylvania, have invented certain Improvements in Fountain-Pens, of which the following is a specification.

My invention relates to certain improvements in the detail construction of fountain-pens, having for its object the provision of a novel formation and arrangement of parts, which while being of such a nature as to not easily get out of order shall be so made that its members are readily removable for cleaning or inspection.

A further object of the invention is to provide a fountain-pen including a filling-piston, which shall be of such a construction that it will not be likely to be rendered inoperative by a thickening or gumming of the ink used.

It is also desired that the feeder for the pen shall be of such a construction as to be easy to remove for cleaning, while at the same time being efficient under working conditions.

These objects I attain as hereinafter set forth, reference being had to the accompanying drawings, in which—

Figure 1 is a longitudinal sectional elevation of a fountain-pen, showing my invention as applied thereto; and Fig. 2 is a perspective view of a modification of the feeder and the piece for holding said feeder and pen in place in the end of a fountain-pen.

In the above drawings, A represents the case of a fountain-pen, having a cylindrical bore and provided at its rear end with a screw-threaded portion a, the bore at said end being reduced by an internal flange a'.

A' is a continuation of the case A and is provided with internal screw-threads, so that it may be screwed upon the threaded portion a of the case, it being noted that said cap A' is closed at its rear end, while the case A is open at both ends when considered independently of the apparatus described hereinafter.

The forward end of the case is slightly tapered for the reception of a projecting cap, (indicated in dotted lines,) and this end has

fitting within it a pen b and a substantially cylindrical plug b', preferably of cork or other suitable material, which serves to hold said pen in position. A feeder b², having its end bent, as indicated at b³, is confined between the plug and the pen and is, though not necessarily, fixed to said plug by means of one or more pins b⁴.

It will be noted that the feeder b² is of flat material and is placed to be against the concave under side of the pen, thereby providing a channel between itself and said pen for the outflow of ink. The downwardly-bent portion b³ of said feeder rests against the rear face of the plug b', so that the removal of the latter is assured whenever the feeder is removed and that without danger of loosening the means whereby said feeder is held to the plug, the function of the downwardly-bent end in this case being to prevent strain upon the pins comprising said means when the plug is withdrawn from the case by pulling outwardly upon the pen and the feeder.

The piston D preferably consists of an internal rod d, having fixed to it a head d' of slightly less diameter than the bore of the case A, and there is fitting over said rod a tubular section d², having an enlarged end portion d³, which projects outside of the main portion of the case A, but within the part A'. This tubular portion is preferably formed of hard rubber and is removably connected to the rod d, so that a body of packing, leather, rubber, &c., may be confined between its forward end and the piston-head d', as indicated at d⁴.

When it is desired to fill the pen, the cap A' is removed, and with the forward end of the pen and casing immersed in ink the piston is slowly pulled outwardly, thereby drawing said ink into the case through the passage between the pen and the feeder b². When the piston has been drawn rearwardly until further movement is stopped by the flange a', the cap A' is replaced and the pen is ready for use. Should the ink feed slowly or imperfectly at any time while the pen is in use, its flow may be compelled or hastened by a slight

inward motion of the piston, although ordinarily this is not necessary, as the ink will usually feed under the influence of gravity. The rearward motion of the piston is limited 5 by the flange a' , as above noted, which prevents its being withdrawn from the case in the event of its being moved rearwardly to too great an extent. Should it be desired to clean the device, both pen and feeder are grasped by 10 the fingers and pulled away from the body of the case, thus also removing the cork plug and permitting free access to the interior of the case. It will be noted that the cleaning may be materially assisted by the use of the piston, 15 which can readily be manipulated, so as to thoroughly remove any solid particles which may have been deposited from the ink.

By providing the small tube-section d^2 , fitting over the piston-rod d , I am enabled to 20 very cheaply construct the plunger of my improved device, since by its use the packing d^4 can be very quickly and easily put in position or replaced. Moreover, it is possible by use of this construction to employ a form 25 of packing which could not otherwise be employed, unless the head d' of the piston-rod were screwed onto said rod, which construction would increase the cost of the device as well as weaken it.

30 I claim as my invention—

1. In a fountain-pen the combination of a casing open at its forward end and provided with a pen, a feeder for the pen and a piece closing said forward end of the casing, said 35 feeder having means for positively engaging said piece, said means being capable of transmitting motion from the feeder to the piece, substantially as described.

2. The combination in a fountain-pen, of a 40 casing having an opening in its forward end, a substantially cylindrical plug therein, a feeder fixed to said plug, and a pen adjacent to said feeder, substantially as described.

3. The combination in a fountain-pen of a 45 plug normally serving to partially close one end of same, a pen, a feeder adjacent thereto, said feeder having a projecting portion formed

to positively engage the plug, substantially as described.

4. The combination in a fountain-pen of a 5c casing having its forward end open, a substantially cylindrical plug fitted into said casing, a feeder adjacent to the plug and having its rear end formed so as to positively engage the rear face of said plug and capable of transmitting motion thereto, with a pen confined between said feeder and the case, substantially as described.

5. The combination in a fountain-pen of a 6c casing having a substantially cylindrical bore, a pen having means provided to retain it in one end of the casing and a piston within said casing, said piston including a head portion and a rod fixed thereto, a tubular portion fitting over said rod and extending substantially 65 the entire length thereof, with a body of material confined between the piston-head and said tubular portion, substantially as described.

6. The combination in a fountain-pen of a 7c cylindrical casing having a pen in one end, a cap for the other end of the casing, an inwardly-projecting flange at the cap end of the casing and a piston movable within the casing, said flange being placed to limit the rearward motion of said piston, substantially as 75 described.

7. In a fountain-pen, the combination of a 80 casing having a substantially cylindrical bore, a cap for said casing, a pen and a piston, said piston including a rod having fixed to it a head, a tubular portion extending over the greater portion of said rod and having upon its rear end a head portion with a body of material in engagement with the interior walls of the casing and confined between the piston-head and the forward end of said tubular portion, substantially as described.

In testimony whereof I have signed my name to this specification in the presence of two subscribing witnesses.

ALFRED B. DAVIS.
